UNITED STATES PATENT OFFICE.

GEORGE MACBETH AND MALCOLM MACBETH, OF LIVERPOOL, ENGLAND.

CASH-REGISTER.

1,272,977.

Specification of Letters Patent.

Patented July 16, 1918.

Original application filed January 8, 1915, Serial No. 1,263. Divided and this application filed October 12, 1916. Serial No. 125,244.

To all whom it may concern:

Be it known that we, GEORGE MACBETH and MALCOLM MACBETH, subjects of the King of England, residing at 4 Streatham avenue, 5 Sefton Park, Liverpool, in the county of Lancaster, England, have invented new and useful Improvements in or Connected with Cash-Registers, of which the following is a specification.

10 This invention has reference to apparatus used in connection with the selling of goods and the indicating and recording of cash received for same, including the indicating to the purchaser the sum paid to, and received by the seller, such apparatus being generally called "cash registers"; and the type to which the apparatus and invention specially relates, is that wherein the keys or like parts are moved in by hand, and operate 15 mechanisms for unlocking the hand lever and for unlocking and releasing a rectilinearly movable differential member, which moves at right angles to the mechanism, and is freed thereby; this application being a 20 division of our U. S. application filed Jan. 25 8/15, Serial No. 1263.

Under this invention, the value keys operate directly upon, that is, make contact with, a device, which is adapted to lock and release 30 the differential member, which in the present case is in the form of a "gate" or frame provided with angular parts which make contact with pressed in or operated amount or value keys, and control the extent of movement of the gate; the gate being adapted to move in a line transverse to the rows of keys with which each angular part is adapted to co-act.

The invention is illustrated in the annexed drawings, in connection with which it 40 will be described; while the features which are claimed as novel, are set out in the claiming clauses concluding the specification.

45 In the drawings, Figure 1 is a cross section showing the machine; Fig. 2 is a front view, and Fig. 3 is a plan in section. Figs. 4, 5, and 6 are detail views of the lower part of Fig. 1.

50 Referring to the drawings, 1 are the keys, constituting the primary hand operated parts of the machine; and in the case shown, the keys have a movement in the horizontal

plane, and are arranged in two sets, one on each side of the center in a plurality of rows. 55 2 is a hand actuated part or lever which contacts with the keys 1 in using the machine and which performs the various functions hereinafter described.

The handle or lever 2 is disposed in the center of the machine, and is fixed on a transverse spindle 3 supported at its ends by outside members 4 of the main frame, and near the lever by the inner members 5 of the frame, between which it works. 60 65

Other transverse shafts extend across the machine between the outside frames 4 for working various parts. Namely, there is below a shaft 8 carrying certain controlling gear; a shaft 9 above this which carries parts 70 and a shaft 10 at the upper part supported in the frames 4 which carries the cash indicating parts.

Besides these shafts there is a short shaft 11 above and near the shaft 9, supported in 75 the inner frame parts 5, and carrying the mechanisms connected with the locking and releasing of various parts.

The keys 1, that is the spindle parts of them are supported by plates 13 fastened on 80 outwardly projecting parts 14 on the bracket 15 (Fig. 3), which are fixed by studs 17 on to transverse horizontal members 16, connecting the frames 4 and 5 together, and preferably cast with studs. 85

Each set of keys 1 operates in connection with a gate device 20, there being one gate for each set of keys. Each gate includes side frame members and diagonally arranged cross bars 22, the side frame members having 90 bosses 24 slidably mounted on guide-rods 25. The gate is thus supported for vertical movement and is provided with upwardly extending rack-bars, which in the vertical movement of the gate, operate the drums, as 95 hereinafter described.

Any of the keys 1 of one set, when moved in by hand, acts upon a swinging locking and releasing means, consisting of horizontal plates 26 fixed on vertical plates 27, 100 which carry at their upper ends, a plate 28, which operates in connection with the gate so far as vertical movement of it is concerned, and constitutes the vertical locking means. Namely, when a key is operated, it 105 acts upon one of the bars 26 or 28, as the

case may be, and presses this locking device or means back, and so moves the upper plate 28 back, and out of the way; that is, out of the plane of the upper bar 22 of the gate, 5 which it normally stands above. One of the locking and releasing means is provided for each gate, and for each set of keys.

The plates 26, 28 and the bars 27, constitute a species of swinging frame, which 10 is supported from a fixed part of the machine by suspension links 29, so that it is capable of being moved horizontally; and when it is so moved by a key, so that the bar 28 is moved away back out of the plane 15 of a gate bar 22, it allows it to move up, which is effected by a spring 30, as herein-after described; and according to which key is moved in, so will be permitted the degree 20 of movement vertically of the gate, and this is governed by the diagonal inclined bars 22 of the gate.

Thus, according to which key is moved into the path of the diagonal gate bars 22, so will be the upward amount of movement 25 of the gate; the distance from the axes of the keys of the different rows, and the active edges of the different diagonal bars 22 vertically, being different in the rows of keys, starting at the smallest at one end of the top 30 row, and finishing with the largest at the opposite end of the lowermost row.

The machine shown is adapted for indicating two denominations of money; and has a fac-simile arrangement, and duplication 35 of key parts, and gate device on each side of the machine.

One, say the right hand set of keys, and gate device, may be used for operating the cents indicating mechanism; and the other 40 set for operating in connection with the dollars indicating mechanism.

The gate, when operated, and after each actuation, is moved down to its normal or zero position (shown in the drawings) by 45 the hand actuated part or lever 2, and is held there by the plate 28 of the swinging frame 26, 27, by its lower edge standing above the upper edge of the upper diagonal gate bar 22.

50 By this form and arrangement of gate device, no matter what key 1 is actuated, it acts upon a part of the swinging frame (26, 27, 28) and frees the gate, so that it can rise vertically; the swinging frame therefore 55 constituting a common locking and releasing device of the gate.

The swinging frame 26, 27, 28 is supported by the links 29, through horizontal backwardly projecting bars 32 fixed to the back 60 of the frame, which their lower ends are hinged to.

Connected with the locking and releasing frame device 26, 27, 28 there is an arm or bar 33, the inner end of which is bifurcated 65 or in the form of a fork, which is supported

by the hinge rod 34 connecting the links 29 and the bars 32.

This bar 33, on its forked end has a projection 35 adapted to act on a lever or arm 36 fixed on the transverse shaft 11, and normally pressed against it by a spring 37, which pulls on a projecting arm or lever 38 connected with one of the arms 36. These arms 36 are for the purpose of operating the money indicating cents and dollars 70 drums 39 and 40 Fig. 2; namely, one of the arms 36, the left hand one, acts upon a small bell-crank lever 41, which through a link 42 acts on an arm 43, fixed on a transverse shaft 44, on which are fixed two holding and 75 releasing pawls 45, one of which acts on a ratchet wheel 46, fixed on a sleeve 47, loosely mounted on the shaft 10, to which the two inside dollar drums 40 are fixed.

The other, namely, the right hand holding and releasing pawl 45, works in connection with a ratchet wheel 50, fixed on the spindle 10, to which the two outer cents drums 39 are fixed; so that these holding and releasing pawls 45, being both fixed on 90 and moving with the shaft 44, move into and out of engagement with the two ratchet wheels 46 and 50 together.

When therefore, the bell crank lever 41 is moved (which takes place whenever a key 95 is pressed in) the pawls 45 will be removed from the ratchet wheels 46 and 50, and free all the money indicating drums, two of which will indicate the data on them from the front; while the other two will indicate 100 from the back.

The cents and dollars drums 39, 40, are themselves rotated when the machine is used, by upwardly projecting parts 53 on the gates 20, having on the upper end of each a toothed 105 rack, which engages with a toothed pinion 54, formed on a sleeve 54^x. One of these pinions 54, and its sleeve 54^x, namely, that on the left hand side, is loosely mounted on the sleeve 47 surrounding the spindle 10; and to 110 the sleeve 47 the drums 40 (to which the ratchet wheel 46, is fixed) is fixed. On the sleeve 54^x is an arm 55, having a bent over end 55^x, which operates on an arm 62, loosely mounted on the sleeve 47, and working between two projections on the face of the wheel 46, against which it lies.

A coil spring (not shown in the drawings) is connected at one end with the sleeve 54^x, around which it is wound, and at the other end to a part of the loose arm 62. The arm 62 has a certain amount of free movement between the stops, which is necessary for the actuating of the mechanism. In action when the wheel 54 is turned by the rack 53, the 125 ratchet wheel 46 of the two drums 40 will be revolved. The parts are so arranged, that when after the drums 40 have been moved by the racks 53 to a given position, they will be returned through the strain in the 130

springs, when the holding pawl 45 is removed from the ratchet wheel 46.

The other pinion 54 is also fixed on a sleeve 54^x as the former, and has an arm 55 which operates the loose arm 62, working in connection with the ratchet wheel 50, and a spring, similarly as in the left hand drum mechanism.

The right hand drum 39 is fixed to the 10 ratchet wheel 50, and to the spindle 10; and the left hand drum 39 is also fixed to the spindle, so that when this right hand mechanism is operated, the left hand drum 39 moves too.

15 The case of the machine—not shown—within which the whole of the parts will be placed and inclosed, has windows in it at the front and back say in the same horizontal plane as the spindle 10, through which the 20 data on the drums 39, 40, will show.

It is to be noted that while the above described gate 20 has been specified as being released, and moves upward by a spring 30, it does not do so at the mere releasing of the 25 gate by the swinging frame (26, 27, 28) but is moved only by the spring when the controlling mechanism actuated by the handle 2, is operated. It is also to be noted that while in the case shown and described the gate is 30 moved upward by means of a weight, as a modification it may be arranged to move downward by its own weight.

With regard to the handle 2, this is only moved after the keys 1 have been actuated, 35 and it performs various functions hereinafter described; and when the machine is in the normal condition, the handle is engaged and held by a catch or detent 70, Fig. 1, loosely mounted on the shaft 11; its end 40 engaging with the catch 71 on the handle. But when a key is pressed in, and the releasing and locking frame 26, 27, 28 and parts above described, are actuated, the catch 70 is actuated, and frees the hand operated lever 2.

45 In the construction shown, this freeing action is effected by an arm 72 fixed on the shaft 11, which acts on the arm of the catch 70 (through a bell crank trigger 73 hereinafter described) and operates it; the 50 shaft 11 being as stated, actuated, that is, partially rotated, when the key is moved in.

The hand actuated part or lever 2 is now free to be moved.

55 Simultaneously, with the movement of the catch 70, by the arm 72 the trigger 73 will be moved. This trigger acts as a detent to and works in connection with two rack bars 74, one on each side of the machine, which operate in connection with the gate 20, so that 60 when the trigger 73 is actuated as just described, it moves out of the path of and frees the rack, and so the gate 20—which is connected with the rack 74 by bars 75, and slotted ends 76 on them through which pins 65 77 pass through the slots—is freed, and can

then be moved up by the spring 30 when the handle 2 is actuated, but not before.

With reference to the means of actuating the gate as above described, this is effected through the spring 30, but this spring can 70 only act on the gate when it is freed, it being normally unable to act by parts, hereinafter described, between it and the gate, which hold it down in its lowermost position.

This holding means consists of a weight 80 75 fixed on to the transverse shaft 8, on the back of the machine, and having a forwardly projecting part 86, connected by the link 81 at its front end, with the projection part 82, of or connected with the hand lever 2. The 80 weight 80, of course will exert greater force than the spring 30.

The spring 30 is connected to a lever 83 loosely mounted on the shaft 8, and extending toward the front of the machine, 85 where it is connected by a link 84 with the bottom part 85 of the gate 20; and the weight 80 rests and acts on the lever 83 through an adjustable pin 87, on the end of which the dotted shaded part (see Fig. 1) 90 of the weight 80 rests. Thus when the weight 80 is resting on this pin 87, it keeps the lever 83 down, and the spring 30 in tension, and also holds the gate 20 down; but when the lever 2 is pulled forward, the 95 weight 80 will be lifted off the pin 87, and so the lever 83, and gate 20 will be freed, and the spring 30 can lift them up.

The movement of the weight 80 by the hand lever 2 will be much greater than 100 the upward movement of the gate 20 and lever 83; but this extra movement does not affect the gate's action.

The function and effect of the weight 80 is to govern or regulate the upward movement of the gate 20. 105

With regard to the mode of operating the hand lever 2, it is the duty of the user to move it to its full stroke or extent.

Thus in all cases, when the gate reaches 110 the end of its up-stroke, whether a portion of the total proper stroke or the whole of it, the weight 80 moves away from the spring pressed arm 83, whose motion upward is limited through the limited movement of the gate.

In the latter portion of the outward stroke of the hand lever 2, a part on it, namely the boss of the double bell crank levers 90 arranged on each side of and pivoted on the part 82, strikes the lower end of the projecting bar 33 of the swing frame 26, 27, 28, and lifts it, and so lifts the projection 35 above the end of the arm 36, so that the spring 37 acting on the arm 38, can 125 turn the shaft 11, and so cause the arm 72 to move down; the catch 70 thereby being free to move down also into the engaging position.

In this movement of the arm 72, it moves 130

away from the trigger or detent 73, the lower end of which will be pressed against the face of the rack bar 74, so that when this rack moves down till the upper end of the rack proper is below the level of the lower end of the trigger 73, it—the trigger—can be moved by a spring 91 over to the locking or holding position as seen in Fig. 1; whereupon the upper arm of the 10 detent 73 will come on to the nose of the lever 72, when the catch 70 can drop down into the engaging position.

By this outward movement of the hand lever 2 as stated, the gate 20 will have been 5 freed so as to be able to rise; and when this latter action takes place, the dollars and cents drums 40 and 39, will be actuated by the racks 53.

20 The next operation is the return action of the hand lever 2. In the first position of this return stroke, the lower outer end of the double hinged trigger 90 (which is normally pulled up by a spring 93) acts upon the type wheel actuating rack parts 25 74; namely, this trigger acts on a block 94 on each of the bottoms of the rack bars 74, and moves these rack bars down; and in this operation the weight 80 will also have been lowered by the lever 2, and will 30 have come in contact with the pin 87, on the arm 83, and so moved it down; and as this arm or lever 83 moves down, the gate 20 is pulled down by it. So the rack bars, and the gate, move down together, but their 35 movement is effected by independent means.

The lowermost position of the lever 83 is governed by a strop 95 on the bottom of the machine, with which it comes in contact.

Near the end of the stroke of the lever 2, 40 the trigger 90 will move off the blocks 94, and out of their paths, whereupon the rack bars 74 can be moved by the springs 78, so that the top of the racks will come on to the end of the trigger 73.

45 The inner end of the cash drawer of the register (not shown) will lie in the base of the frame of the machine, immediately under the shaft 3, and will come up to the vertical part 97 of the frame, having on its end an eye or engaging part in the well known way, which is adapted to engage with the end of the hook lever 98 hinged to the frame, and normally pulled by a spring 99.

50 In and by the latter portion of the stroke of the hand lever 2 this catch 98 is depressed, and frees a drawer, this being effected by a projection (not shown in the drawings) on the lever 98 with which one 55 of the tappets 90 comes in contact; and it slips off same similarly as the tappet lever 90 slips off the blocks 94 of the rack bars 74.

Also toward the latter portion of the stroke of the lever 2, a pin 102 on the weight

80 comes in contact with an arm 103 pivoted 65 on the frame of the machine, and connected by a rod 60 with one of the arms 59 of the shutters 56, and pulls one down, and so the other up, to the position shown in Fig. 1, so as to expose the back and front numerals 70 of the numeral drums 39, 40. During this action the ratchet wheel 57 will click over the teeth of the holding pawl 63, which it can do through the "give" of the spring 65.

Thus when this action last described takes 75 place, and when the return movement and operation of the hand lever is nearly completed, the amount of the transaction will be indicated by the cash drums, both at the front and the back of the machine. 80

Regarding the actuating keys, they have locking and interlocking arrangements, by which those actuated will have been held in position to which they were moved, up to this point of the cycle of operations of the 85 machine and they are subsequently to this time, adapted to be released.

The other keys will also be locked by the interlocking mechanism in their outer and stationary positions, and must therefore now 90 be freed.

This freeing action is also adapted to be effected during the last portion of the stroke of the hand lever 2, but it must be after the gate is fully drawn down, and held by the 95 weight 80.

The interlocking arrangement shown in the drawings, comprises continuous hinged double pawls 110, hinged at their ends to stationary bars 111, fixed on the frame parts 100 14; and they are normally pulled to the position shown in Fig. 1, by a spring 112, fixed at one end to a bar 111, and at the other end to vertical movable bars 113, which are connected to the pawls 114 by pins on the adjacent ends of each of the several continuous pawls, which pass through the bars. Thus by the spring 112, all the pawls normally, will be held in the position shown in Fig. 1. 110

The bars 113 of the set of keys, on each side of the machine, are connected together by a pin 117.

The pawls are of a continuous plate form, with a continuous catch or hook on each end, of the shape seen in Fig. 1. When a key 1 is pushed in, a curved cam shaped part 115, comes in contact with the pawl catch 110, and moves it up about its hinge; and when the key has been pressed in a certain amount, the front catch of the pawl 110 passes the end of this cam surface, and the catch is pulled up or tilted by the spring 112, and the pawl catch 110, falls into the notch 116, and so locks the key. The key so actuated 120 remains in this locked position until practically the end of the inward or return stroke of the hand lever 2. Also by the 125

pressing in of a key 1, the back catches of the pawls 110 will move into the gaps 124 of the spindles of the keys, which have not been actuated, and locks them.

- 5 In this action a hook 120 at the side of the lever 2, comes in contact with the catch 121 on a bar 122, connected at its upper end to the pin 117; and this catch 120 at the end of the stroke of the lever, engages the hook 121 momentarily, and pulls the rods 113 down, and so trips the front catches of the pawls 110 up, so as to be clear of the notches 116.

At this stage the bar 122 is knocked out of engagement with the catch 120 by the adjustable tappet device 123 on the handle 2; and then the bars 113 are free to be moved up by the spring 112, and this takes place; and so the tumbler pawls 110 are reversed, 20 and the key which was pressed in can move out, all those keys which have not been used, and have been held and locked by the back catch ends of the tumbler pawls 110 engaging with the back gaps 124 of the keys are 25 freed.

When the key that was pressed in presses by the cam surface 115, the front end of its pawl 110, this act, through the construction and arrangement described, causes all 30 the back catches of the pawls to fall into gaps 124 in all the other key spindles.

When this takes place, by the keys being now moved to their outer positions, the locking and releasing swinging frame 26, 27, 28, 35 is enabled to swing in, and move forward over the uppermost bar 22, of the gate 20 and so lock the gate in its normal position vertically; while before this it was held, and in the position in which the gate is unlocked.

40 What is claimed is:—

1. In a cash register, a plurality of longitudinally movable keys, cam parts on each key, a unitary locking and releasing pawl device common to all said keys and cam parts and operable by any of said cam parts, said keys having parts to be engaged and disengaged by said pawl device.

2. In a cash register a plurality of longitudinally movable keys, cam parts on each, 50 a unitary locking and releasing pawl device common to all said keys and cam parts, and operated by any of said cam parts; parts on the keys to be engaged and disengaged by the said pawl device, a hand operated part for operating the register, and a tappet device operated by said hand actuated part to move the pawl device out of engagement with a key which has been pressed inward, and free the keys which 55 have not been pressed in; substantially as set forth.

3. In a cash register a plurality of longitudinally movable keys, cam parts on each, a unitary locking and releasing pawl device

common to all said keys and cam parts, and 65 having a front catch and a back catch, operated by any of said cam parts; parts on the keys to be engaged and disengaged by the said pawl device; a spring to operate the pawl devices in one direction; the cam part 70 being adapted to act on the pawl when the key is pushed in a certain amount, to cause the front catch of the pawl which has passed the end of the cam surfaces to engage with a locking or detent part on the key, and 75 lock it; substantially as set forth.

4. In a cash register a plurality of longitudinally movable keys, cam parts on each, a locking and releasing pawl device common to all said keys and cam parts, to be 80 operated by any of said cam parts; parts on the keys adapted to be engaged and disengaged by the said pawl device; a spring to operate the pawl devices in one direction; the cam part being adapted to act on the 85 pawl when the key is pushed in; a certain amount to cause the front catch of the pawl which has passed the end of the cam surfaces to engage with a locking or detent part on the key, and lock it, and also to move 90 the back catches of the pawls into locking or detent parts at the opposite side of the cam surfaces to the front locking or detent part so as to lock the keys not actuated; 95 substantially as set forth.

5. In a cash register a plurality of longitudinally movable keys; cam surfaces; double detent pawls; detent recesses or parts, respectively, on the front and back ends of the cam surfaces; means connecting 100 the pawls together and to the different sets of keys; means for rocking the pawls upon their pivots altogether; a hand actuated part for actuating the machine, and a tappet device operated by a hand actuated part, 105 for actuating said pawl moving means; a detent for holding the pawls in the back engaging parts 124 of the keys, said detent part being connected with all the pawls of the other sets of keys; and said tappet— 110 operated by the hand actuated part of the machine—being adapted to free said detent, and effect the movement of the pawls out of engagement with the back notches or parts; substantially as set forth.

6. In a cash register, a plurality of longitudinally movable keys, a locking device mounted above all of said keys and comprising a plate having depending catches, means on each key whereby to operate the 120 plate in one direction in the operative movement of the key, each key being formed to be engaged by one of said catches at the limit of movement of the plate under the operation of such means.

7. In a cash register, a plurality of longitudinally movable keys, a locking device mounted above all of said keys and compris-

ing a plate having depending catches, means on each key whereby to operate the plate in one direction in the operative movement of the key, each key being formed with notches to be engaged by one of said catches when the keys are in normal position and with notches to be engaged by the other of said catches when the key has been moved to operative position.

In testimony whereof we have signed our names to this specification in the presence of two subscribing witnesses.
